VISCOSITY REGULATED FLUID FUEL CONTROL MEANS

Lawrence L. Finnigan, Seattle, Wash.

Application April 4, 1933, Serial No. 664,306

14 Claims. (Cl. 158—36)

My invention relates to the art of controlling the discharge of oil from the atomizer nozzle of an oil burner and the general object of my invention is to provide fully automatic means for preventing the discharge of oil from an atomizer nozzle of an oil burner when said oil is too thick and is not of proper viscosity and permitting the discharge of such oil when the oil is thin enough to be of the correct viscosity to atomize properly and burn efficiently.

In the burning of oil in oil burners of the atomizing type it is essential to have the oil thin enough so that it will atomize properly before efficient combustion can be secured. For this reason it is common practice to thin the oil by heating the same before the oil is fed to the oil burner. The viscosity of oil varies in proportion to the temperature and the generally accepted method of changing the viscosity is to change the temperature.

Knowing the viscosity of the oil as determined by a viscosimeter at a given temperature then the most efficient atomizing viscosity can be determined by temperature alone. I find that the efficiency with which the oil is atomized and burned depends primarily on the viscosity and that the effect of temperature on the atomization is due chiefly to viscosity changes produced by changes of temperature. In one form of my invention I utilize the temperature of the oil for controlling the discharge of said oil from an atomizer nozzle and in this way I obtain a control which is responsive to variations in the viscosity of the oil while in another form of the invention I utilize the viscosity of the oil directly for controlling the discharge of said oil. In both of these types of control I attain the much desired result of controlling the discharge of the oil in response to a change in the viscosity of said oil.

In this application I use the term "high viscosity" to describe oil which is relatively thick and sluggish, and "low viscosity" to describe oil which is relatively thin and of high fluidity.

Oil having a high viscosity is relatively thick and sluggish and hard to atomize properly and consequently it can not be burned efficiently when it is discharged from an oil burner atomizer nozzle. Oil of lower viscosity is thinner and more easily atomized and will produce a more finely divided spray and consequently burns more easily and more efficiently. For these reasons it is desirable to provide automatic means which operates proportional to changes in the viscosity of the oil for preventing the discharge from a burner nozzle of thicker oil of higher viscosity and per-

mitting the discharge from the burner nozzle of said oil only after the viscosity is low enough and the oil thin enough to be properly atomized for efficient combustion as it is discharged from an atomizer nozzle of a burner.

Another object of my invention is to provide a new and efficient circulating head for an oil burner said head having means for maintaining a continuous circulation of oil to a point immediately adjacent the atomizer nozzle without permitting the oil to discharge if the viscosity of the oil is high and further having means for permitting the oil to discharge if the viscosity is reduced to a predetermined fluidity at which the oil is thin enough to permit efficient atomization and burning.

Another object is to provide electric circuit opening and closing means in connection with my viscosity responsive control so that this control can be used with oil burner systems without alteration of the present safety circuits of the same.

Other and more specific objects will be apparent from the following description taken in connection with the accompanying drawings.

In the drawings

Fig. 1 is a plan view with parts removed and other parts broken away, of oil burner control means constructed in accordance with my invention.

Fig. 2 is a sectional view of the same substantially on broken line 2—2 of Fig. 1.

Fig. 3 is a diagrammatic view showing one manner of connecting parts of my control mechanism with the electric circuits of an oil burner system.

Fig. 4 is a fragmentary sectional view on a larger scale of an oil atomizer nozzle and control valve means embodied in this invention.

Fig. 5 is a vertical sectional view of electro-magnetically operated control means constructed in accordance with my invention.

Fig. 6 is a diagrammatic view showing electrical controls and oil flow means.

Figs. 7, 8 and 9 are sectional views respectively of another form of my invention in which the control depends directly on the viscosity of the fuel.

Referring to Figs. 1, 2, 3 and 4, the numeral 10 designates a housing having a plurality of compartments or chambers 11, 12, 12', 13 and 14 provided therein and having a cover member 15 removably secured thereon. The compartment 12' is cylindrical and intersects the compartment 12. A burner pipe 16 is secured to the housing 10 and extends outwardly from one side thereof. A fit-

ting 17 is provided on the end of the pipe 16 and an atomizer nozzle 18 having a delivery orifice is supported at the end of the burner pipe by a cap 20. An atomizer nozzle control valve 21 is positioned adjacent the atomizer 18 and is arranged to seat on a valve seat 22 in the fitting 17. A return tube 23 of smaller diameter than the burner pipe 16 is disposed substantially coaxially within said burner pipe 16 in such a manner as to leave an annular passageway 24 between the outer wall of the tube 23 and the inner wall of the pipe 16. The pipe 16 communicates with the chamber 11 while the tube 23 extends through the chamber 11 and communicates with the chamber 12 and is threaded into a wall 25 which forms a partition between the chamber 11 and the chamber 12.

A valve operating rod 26 is secured to the atomizer nozzle control valve 21 and extends lengthwise through the tube 23 and is secured to a piston valve 27 which is longitudinally movable in the cylindrical chamber 12'. A compression spring 28 engages the piston valve 27 and exerts pressure tending to keep the nozzle valve 21 closed. The spring 28 is adjustably supported by a washer 30 which is engaged by a set screw 31 threaded through a fitting 32 and having a lock nut 33 thereon.

The chamber 13 is positioned below the chambers 12 and 12' and is connected with the chamber 12 by a by-pass port 34 and a relief port 35. A by-pass valve 36 controls the opening and closing of the by-pass port 34 and has a stem 39 which is suitably guided and extends upwardly into the chamber 14. The relief port 35 is opened and closed by the piston valve 27. An opening 34' is provided between chamber 13 and the portion of chamber 12' in which the spring 28 is disposed to prevent back pressure on piston 27.

A jacket member 37 surrounds the pipe 16 and affords a space 38 which is filled with a thermostatic liquid. The space 38 communicates through an opening 40 with a chamber 41 within which is disposed a pressure responsive bellows-like device 42 which is arranged to be compressed upwardly by the fluid from the space 38. A stem 43 is connected with the bottom of the pressure responsive device 42 and extends upwardly through the upper end wall 44 of the chamber 41. The upper end of this stem 43 is connected with suitable quick throw mechanism which controls the opening and closing of the by-pass valve 36. A compression spring 45 opposes the pressure of the fluid against the bottom side of the pressure responsive member 42.

The quick throw mechanism may be of various different forms. One operative quick throw mechanism may embody a lever arm 46 fulcrumed at 47 and having one forked end 48 which is connected with the stem 43. The other end of the lever arm 46 is connected by a link 50 with a toggle member 51 which is pivotally mounted on a shaft 52. The shaft 52 is supported in relatively fixed bearing means 53 and has two crank arms 54 and 55 secured thereto. The end of the crank arm 54 is forked and engages with a collar 56 on the stem 39 of the by-pass valve 36 whereby the by-pass valve 36 may be moved into open or closed position by oscillation of the crank arm 54. The crank arm 55 extends in one direction from the shaft 52 while the toggle member 51 extends in the opposite direction. The non-pivoted ends of

the crank arm 55 and toggle member 51 are connected with each other by a tension spring 57; the arrangement being such that the line of pull of the spring 57 may cross from one side to the other of the center of the shaft 52 due to movement of the toggle member 51 and may thus cause the crank arm 55 to be snapped up or down thus snapping the crank arm 54 up or down at the same time and opening or closing the by-pass valve 36 by a quick movement.

An electric switch 58, which may be of conventional mercury contact type may be secured to the lever arm 46 and connected in an oil burner circuit in such a manner as to prevent a safety circuit which forms part of the usual oil burner control from completely stopping the operation of the burner mechanism when the oil is circulating through the burner head but is not discharging from the nozzle. One typical oil burner control system of this nature is shown in Fig. 3, in which 105 is a motor which may furnish power to drive the pump and blower which supply oil and air to the burner. 106 is a switch controlling the supply of current from a source 107 to this motor. 108 is an electromagnetic operating means for this switch. 109 is a control circuit controlling the electromagnetic operating means 108. 110 and 111 are automatic or thermostatic control switches of any conventional type provided in circuit 109. 112 is a switch in circuit 109 which may be operated either by hand or preferably by an electromagnet 113, which electromagnet 113 is usually time delayed in its operation. 114 is a safety circuit for the burner, which safety circuit 114 is connected with the electromagnet 113 and usually includes a stack switch 115 or like circuit control device which, in the usual oil burner system is capable of functioning to energize the electromagnet 113 and to stop the operation of the burner in case of flame failure. When my viscosity control is used the burner will not light off promptly after it is put into operation but should continue to circulate oil until said oil has been reduced to proper viscosity before my oil is sprayed from the atomizer nozzle 18. Also if the viscosity of the oil becomes too high during the operation of the burner the nozzle control valve 21 will be closed and the burner flame extinguished but the oil circulating mechanism should continue to operate and the burner should light off again as soon as the viscosity of the oil has been reduced enough to open the nozzle control valve 21. The stack switch 115 in the usual oil burner safety circuit, if used in connection with my viscosity control and without alteration of the safety circuit, would stop the burner motor 105 before the circulating oil had become thin enough to cause the nozzle valve 21 to open. To avoid this I interpose the switch 58 in the safety circuit 114 and arrange this switch so that it will open or break the safety circuit 114 at all times when the nozzle valve 21 is closed thus neutralizing any operation of the stack switch 115 which might otherwise tend to stop the burner motor 105. When the nozzle control valve 21 is open then the switch 58 will be closed and the safety circuit of the burner will be effective in the usual manner. The neutralizing of the safety circuit when the nozzle valve 21 is closed does not lessen the safety of the burner as no oil can be discharged when the nozzle control valve is closed.

The chamber 11 has an oil inlet port 60 which may be connected by a pipe 61 with any suit-

able source of supply of oil under pressure. The chamber 13 has an oil outlet port 62 which may be connected with an oil circulation pipe 63. The oil inlet and outlet pipes may connect with any suitable source of supply of oil, not shown, and may further have pump means and heating means associated therewith whereby the oil may be circulated and heated and placed under pressure as more fully hereinafter explained in connection with Fig. 6.

In the operation of the device disclosed in Figs. 1, 2, 3 and 4 the control of the nozzle valve 21 is accomplished by variations in the temperature of the oil. As the viscosity of the oil varies with the temperature this constitutes one practical way of controlling the discharge of oil from the burner nozzle in accordance with the viscosity of the oil. During the operation of this device oil under pressure is admitted to the chamber 11 through the port 60. If this oil is cold it will be relatively thick and the viscosity will be high and this cold oil will flow outwardly through the annular passageway 24, thence return by way of the return tube 23 to the chamber 12, thence it will flow through the by-pass port 34 into the chamber 13 and out through the outlet port 62 from which it may be re-circulated through suitable heating means. It will be understood that the by-pass valve 36 will always be open when the liquid in the chamber 38 surrounding the pipe 16 is cold. As the temperature of the circulating oil increases the viscosity thereof will be lessened and this warmer oil will heat up the liquid in the chamber 38 thereby producing expansion of said liquid, which expansion will be exerted under the bellows-like member 42. This will lift the stem 43 and swing the outer end of the lever 46 downwardly and depress the outer end of the toggle member 51 until the line of pull of the spring 57 passes below the center of the bolt 52 whereupon the cranks 55 and 54 will both be snapped downwardly and the by-pass valve 36 will close the port 34. This closing of the by-pass valve 36 will not occur until the oil has been heated up sufficiently to be of proper viscosity for efficient atomizing and burning. As soon as the by-pass valve 36 closes oil pressure will build up in the chamber 12 and move the piston valve 27 to the right from the position shown in Fig. 2, thus opening the nozzle valve 21 and allowing oil to be sprayed from the atomizing nozzle 18. While the by-pass valve 36 remains closed the piston 27 will hold the nozzle valve 21 open and said piston may uncover or partially uncover the relief port 35 thus keeping the oil pressure at the nozzle constant and permitting excess oil to escape through the relief port 35 and re-circulate. As long as oil above a predetermined temperature is flowing through the annular passageway 24 it will keep the thermodynamic liquid in the chamber 38 heated and expanded, the stem 43 will be held in an elevated position and the by-pass valve 36 will remain closed and the burner will continue to operate normally. If the temperature of the oil drops below the predetermined minimum temperature the liquid in the chamber 38 will contract thus permitting the spring 45 to move the stem 43 downward and actuate the quick opening and closing mechanism which will open the by-pass valve, whereupon the pressure against the piston 27 will be relieved and the nozzle valve 21 closed. This stops the discharge of oil from the burner until the oil is again heated up enough to close the by-pass valve 36 and re-open the nozzle valve 21.

75 The switch 58 will be in an open circuit position

when by-pass valve 36 is open and nozzle valve 21 closed and in a closed circuit position when the by-pass valve 36 is closed and nozzle valve 21 open as hereinbefore explained, to prevent operation of the safety circuit of the burner when the nozzle valve 21 is closed and the oil circulating but not discharging from the nozzle.

In Figs. 5 and 6 I have shown an alternative construction in which an electromagnet is employed as a quick opening and quick closing means for the by-pass valve. In this disclosure is shown a housing having chambers 66, 67, 68 and 69 which correspond with the chambers 11, 12, 12' and 13 respectively of the type of control first described, Fig. 5 also discloses a burner pipe 70, burner tube 71, by-pass port 72, relief port 73, and spring loaded piston 74 all similar to the previously described corresponding parts. A by-pass valve 75 arranged to close the by-pass port 72 is connected with the core 76 of an electromagnet 77. The circuit to the electromagnet 77 is controlled by the temperature of the oil which circulates through the pipe 70 and tube 71. When the temperature of this oil is below a predetermined minimum then the circuit to the electromagnet 77 will be closed and the by-pass valve 75 snapped open and held open until the oil is again heated up sufficiently to open the circuit to the electromagnet 77 whereupon the by-pass valve 75 will be permitted to close by gravity. The chamber 66 has an oil inlet port 78 and the chamber 69 has an oil discharge port 118. The control of the circuit to the electromagnet 77, see Fig. 6, will preferably be by means of a thermostatically operated switch 119 which is located so that it will be controlled by oil returning through pipe 120 to a tank 122. The oil may be drawn from tank 122 through pipe 123 to pump 124 and may then pass through pipe 125, oil heater 126 and pipe 127 to the intake port 78, thereby completing an oil circulation circuit. Circuit wires 128 may extend between the switch 119 and the electromagnet 77.

In Figs. 7, 8 and 9 I have disclosed control means which is operated by the viscosity of the fluid fuel. In this disclosure I provide a housing 80 having chambers 81, 82, 83 and 84. An oil inlet 86 connects with the chamber 81. A tapered viscosity control valve 87 is adjustably supported within a tapered passageway 88 in the wall which separates the chambers 81 and 82. An oil burner pipe 89 communicates with the chamber 82. A return tube 90 coaxial within the oil burner pipe 89 extends back through the chamber 82 and communicates with the chamber 84. An axial nozzle valve control rod 91 disposed within the return tube 90 is connected with a spring pressed piston valve 92 in a cylinder 93 which opens into the chamber 84. The cylinder 93 has a relief port 94 communicating with the oil outlet chamber 83. A cylindrical opening 95 is provided between the chamber 81 and the chamber 84 and a piston valve 96 is movably disposed within said opening 95. A spring 97 exerts a downward pressure on the piston valve 96. A relief port 98 connects the cylindrical opening 95 with the chamber 82. A by-pass port 100 connects the chamber 84 with the outlet chamber 83 and a by-pass valve 101 is provided for opening and closing the by-pass port 100. The by-pass valve 101 is connected with the piston valve 96 by a yoke 102 whereby said by-pass valve is opened and closed by movement of the piston valve. A compression spring 103 is interposed between the top side of the yoke 102 and a head 104 on the top of the by-pass valve 101 whereby lost motion in an upward direction is 75

afforded the yoke 102 relative to the by-pass valve 101 as the piston valve 96 moves upwardly. Assuming that the valve 101 is closed, as shown in Fig. 9, and held closed by oil pressure in chamber 84. Then if the piston 96 is moved slowly upwardly the spring 103 will first be compressed until the coils are substantially closed at which time the valve 101 will begin to open, pressure in chamber 84 will be relieved and the spring 103 will snap 10 the valve wide open irrespective of further upward movement of the piston. In closing, the spring 103 holds the valve 101 in the uppermost position as respects the yoke 102 until the end of the valve 101 begins to substantially restrict the outlet of 15 oil through by-pass port 100 and increase the pressure in chamber 84 whereupon the spring allows the valve 101 to snap entirely closed irrespective of downward movement of the piston 96.

In the operation of this viscosity controlled 20 means, when fuel of relatively high viscosity is introduced into the chamber 81 it will be of too thick and sluggish a consistency to flow readily through the restricted port 88 and past the tapered valve 87 and a pressure will be built up 25 in the chamber 81 which will raise the piston valve 96 and open the by-pass valve 101 and port 98. This will permit the oil to flow through port 98 into chamber 82 thence out through burner pipe 89 and back through tube 90 to 30 chamber 84 thence down through by-pass port 100 into outlet chamber 83 from which it may pass outwardly through outlet pipe 83' and be re-circulated. When this occurs the oil will be in contact with the piston 92 but will not exert 35 pressure enough to move said piston 92 against the pressure of a spring 92' because the by-pass valve is open. As long as the high pressure is maintained in chamber 81, the oil will thus continue to circulate without opening the nozzle 40 control valve 21, which may be identical with the valve 21 shown in Fig. 4.

As the viscosity of the oil becomes less and when the desired viscosity is attained the thinner oil will flow more freely past the tapered 45 valve 87, pressure within the chamber 81 will be lessened and the piston valve 96 will close and will close the by-pass valve 101, at the same time. As soon as the by-pass valve 101 is closed the pressure in the chamber 84 will increase and 50 move the piston 92 rearwardly thus opening the nozzle 21 and permitting atomized oil to be discharged from the nozzle. The port 94 will also be partially opened by rearward movement of the piston 92 and will maintain an even pressure 55 and allow excess oil to re-circulate. As long as the fuel remains thin and of low viscosity it will flow past the tapered valve 87 and maintain an approximately equal pressure in the chambers 81, 82 and 84 and the by-pass valve 101 will 60 remain closed. If however the viscosity of the fuel increases and produces a sufficiently high pressure in chamber 81 the piston valve 96 will be raised and the by-pass valve 101 opened thus lowering the pressure against the piston valve 92 and permitting the spring behind said piston 65 valve 92 to move this piston valve and shut off the discharge of oil from the oil nozzle.

The foregoing description and accompanying 70 drawings clearly disclose a preferred embodiment of this invention but it will be understood that this disclosure is merely illustrative and that such changes in the invention may be made as are fairly within the scope and spirit of the following claims.

I claim:

1. In an oil burner, a burner head including a housing, an oil burner pipe extending outwardly from said housing, an oil atomizing nozzle connected with the outer end of said burner pipe, a return pipe within said oil burner pipe, an oil inlet chamber in said housing communicating with the inner end of said oil burner pipe, a by-pass chamber in said housing separate from said oil inlet chamber and communicating with said return pipe, by-pass valve means controlling the pressure of oil within said by-pass chamber by-pass valve opening and closing means connected with said by-pass valve means and controlled by the physical condition of the oil passing through the burner, a nozzle valve positioned between said oil atomizing nozzle and the outer end of said return pipe, a cylindrical chamber communicating with said by-pass chamber, a piston in said cylindrical chamber having one end subject to the pressure within said by-pass chamber, spring means yieldingly engaging the other end of said piston, and stem means connecting said piston with said nozzle valve whereby said nozzle valve is opened by movement of said piston in response to pressure within said by-pass chamber.

2. In an oil burner, a burner head including a housing, a burner pipe extending outwardly from said housing, a return pipe within said burner pipe, an oil inlet chamber within said housing communicating with the inner end of said burner pipe, a by-pass chamber in said housing separate from said oil inlet chamber and communicating with said return pipe, by-pass valve means controlling the discharge of oil from said by-pass chamber, a nozzle valve positioned between said oil atomizing nozzle and the outer end of said return pipe, opening and closing means connected with said by-pass valve means, means responsive to the physical condition of the oil which is being supplied to the burner controlling said opening and closing means, a cylindrical chamber communicating with said by-pass chamber, said cylindrical chamber having a relief port in the wall thereof, a piston in said cylindrical chamber movable to cover or uncover said relief port and having one end subject to the pressure within said by-pass chamber, spring means supporting said piston against the pressure in said by-pass chamber, and stem means connecting said piston with said nozzle valve whereby said nozzle valve and said relief port may both be opened by movement of said piston due to pressure within said by-pass chamber.

3. In an oil burner, a burner head including a housing, an oil burner pipe connected with said housing, an atomizing nozzle connected with the outer end portion of said burner pipe, a return pipe within said burner pipe, an oil inlet chamber in said housing, a second chamber in said housing, communicating with the inner end of said oil burner pipe and having an opening of restricted area communicating with said oil inlet chamber through which oil under pressure will pass from said oil inlet chamber to said second chamber at a rate varying with the viscosity of the oil, a by-pass chamber in said housing communicating with said return conduit and separate from the chamber which communicates with said burner pipe, by-pass valve means controlling the discharge of oil from said by-pass chamber, a nozzle valve positioned between said oil atomizing nozzle and the outer end of said return

- pipe, a cylindrical chamber communicating with said inlet chamber and having a port connecting said second chamber and said cylindrical chamber, a piston valve in said cylindrical chamber 5 responsive to the pressure in said oil inlet chamber and connected with said by-pass valve means for opening and closing said by-pass valve means, said port being arranged to be opened and closed by movement of said by-pass valve 10 control piston, a second cylindrical chamber communicating with said by-pass chamber, said second cylindrical chamber having a relief port in the wall thereof, a nozzle valve control piston in said second cylindrical chamber movable to 15 close said relief port or open said relief port as respects said by-pass chamber and said return pipe and having one end subject to the pressure within said by-pass chamber, spring means supporting said nozzle valve control piston 20 against the pressure in said by-pass chamber, and stem means connecting said nozzle valve control piston with said nozzle valve.
4. In an oil burner, an oil atomizing nozzle, pressure oil supply means communicatively connected with said oil atomizing nozzle, oil return conduit means connected with said pressure oil supply means, a nozzle valve in said pressure oil supply means between said oil atomizing nozzle and said oil return conduit means, a by-pass 25 chamber communicating with said oil return conduit means, a by-pass valve controlling the discharge of oil from and thereby the pressure in said by-pass chamber, by-pass valve operating means connected with said by-pass 30 valve, control devices for said by-pass valve operating means governed by the physical condition of the oil which is being supplied at said oil burner, and pressure actuated nozzle valve opening and closing means controlled by pressure 35 sure in said by-pass chamber.
5. In an oil burner, an oil atomizing nozzle, pressure oil supply means communicatively connected with said oil atomizing nozzle, oil return conduit means connected with said pressure oil supply means, a nozzle valve in said pressure oil supply means between said oil return conduit means and said oil atomizing nozzle, a by-pass chamber communicating with said return conduit means, pressure actuated nozzle valve opening and closing means controlled by pressure 40 in said by-pass chamber, a by-pass valve controlling the discharge of oil from said by-pass chamber, means providing an oil passageway of restricted area in said pressure oil supply means, said oil passageway providing a resistance to the flow of oil varying in proportion to the viscosity of the oil and providing a difference in pressure on the two sides of said passageway higher on the inlet and lower on the discharge 45 side of said passageway said difference increasing as the viscosity of the oil increases and decreasing as the viscosity of the oil decreases, and by-pass valve operating means controlled by difference in pressure on the two sides of said restricted orifice opening said by-pass valve as said difference in pressure increases and closing said by-pass valve as said difference in pressure decreases.
6. In an oil burner, an oil circulating burner head embodying a housing, an oil conduit extending outwardly from said housing, a return conduit within said oil conduit, said return conduit leaving a space between its exterior and the interior of said oil conduit, said housing having 50 an oil inlet communicating with the inner end of 55 said oil inlet communicating with the inner end of said oil conduit and a chamber communicating with the inner end of said return conduit, said chamber having a by-pass port, a by-pass valve controlling the discharge of oil through said port and thereby the pressure in said chamber, an oil atomizing nozzle on the outer end of said oil conduit adjacent an end of said return conduit, a valve controlling the flow of oil through said nozzle positioned between said oil atomizing nozzle and the outer end of said return conduit, opening and closing means connected with said by-pass valve, operating means for said opening and closing means, said operating means being responsive to variations in the viscosity of the oil which is being supplied to the burner, and pressure operated opening and closing devices connected with said nozzle valve 60 and in communication with said chamber whereby said nozzle valve is controlled by said by-pass valve.
7. In an oil burner, an oil circulating burner head embodying a housing, an oil conduit extending outwardly from said housing, a return conduit within said oil conduit, said return conduit leaving a space between its exterior and the interior of said oil conduit, said housing having an oil inlet communicating with the inner end of said oil conduit and a by-pass chamber communicating with the inner end of said return conduit, a by-pass valve controlling the discharge of oil from and thereby the pressure in said by-pass chamber, electromagnetic valve opening and closing means connected with said by-pass valve, thermostatic switch means responsive to the temperature of oil which is being supplied to the burner controlling said electromagnetic means, an oil atomizing nozzle on the outer end of said oil conduit adjacent an end of said return conduit, a nozzle valve controlling the flow of oil through said nozzle positioned between said oil atomizing nozzle and the outer end of said return conduit, and pressure operated opening and closing devices connected with said nozzle valve and in communication with said by-pass chamber whereby said nozzle valve is controlled by said by-pass valve.
8. In an oil burner, an oil circulating burner head embodying a housing, an oil conduit extending outwardly from said housing, a return conduit within said oil conduit, said return conduit leaving a space between its exterior and the interior of said oil conduit, said housing having an oil inlet communicating with the inner end of said oil conduit and a chamber communicating with the inner end of said return conduit, said chamber having a by-pass port, a by-pass valve controlling the discharge of oil through said port and thereby the pressure in said chamber, an oil atomizing nozzle on the outer end of said oil conduit adjacent an end of said return conduit, a valve controlling the flow of oil through said nozzle positioned between said oil atomizing nozzle and the outer end of said return conduit, opening and closing means connected with said by-pass valve, operating means for said opening and closing means, said operating means being responsive to variations in the viscosity of the oil which is being supplied to the burner, and pressure operated opening and closing devices connected with said nozzle valve and in communication with said chamber whereby said nozzle valve is controlled by said by-pass valve.
9. In an oil burner, a burner head including a housing, an oil burner pipe extending outwardly 70 and in communication with said chamber whereby said nozzle valve is controlled by said by-pass valve.

from said housing, an oil atomizing nozzle connected with the outer end of said burner pipe, a return pipe within said oil burner pipe, an oil inlet chamber within said housing and communicating with said oil burner pipe, a by-pass chamber in said housing, separate from said oil inlet chamber, and communicating with said return pipe, a by-pass valve controlling the discharge of oil from and thereby the pressure in said by-pass chamber, a nozzle valve positioned between said oil atomizing nozzle and the outer end of said return pipe, by-pass valve opening and closing means connected with said by-pass valve, means responsive to the physical condition of the oil which is being supplied at the burner for controlling said by-pass valve opening and closing means, a pressure operated opening and closing device connected with said nozzle valve and operated by the pressure in said by-pass chamber, and said by-pass chamber having a pressure relief port controlled by said opening and closing device so as to permit a circulation of oil through said by-pass chamber when said by-pass valve is closed.

25 10. In an oil burner: an atomizing nozzle having a delivery orifice, a conduit for conducting oil to a point adjacent said orifice, a conduit for conducting oil from said point, a valve between said point and said orifice for controlling the flow of oil from said point to said orifice, and means for operating said valve in response to a change in the viscosity of said oil; said last means including a by-pass valve in said second mentioned conduit for reducing or increasing the oil pressure in said second mentioned conduit, and means responsive to a change in the oil pressure in said second mentioned conduit for actuating said valve.

11. A liquid fuel burning apparatus including a burner tube supplied with liquid fuel by means of a pump, an oil heater for said fuel, a valve provided in said burner tube and adapted to open automatically to discharge the liquid for ignition when said fuel reaches a predetermined pressure, a discharge pipe extending from said burner tube, and automatically acting retardation means associated with said discharge pipe and adapted to delay the rise of liquid fuel pressure in the burner tube after the pump has been started and thereby delay the opening of the aforesaid valve. 5

12. A liquid fuel burning apparatus as claimed in claim 11 in which the automatically acting retardation means include a thermostatically-controlled valve provided in the discharge pipe from the burner tube. 15

13. A liquid fuel burning apparatus as claimed in claim 11 in which the automatically acting retardation means include a valve adapted to control the flow of the liquid fuel through the discharge pipe from the burner tube, and means adapted to maintain said valve open after the pump has started and subsequently to close said valve and thereby permit the burner valve tube to 20 open. 25

14. A liquid fuel burning apparatus, comprising: a burner, means for supplying fuel under pressure to said burner, a valve provided in said burner and adapted to open to discharge fuel for 30 ignition upon a predetermined pressure in said fuel, a discharge pipe extending from said valve, retardation means in said discharge pipe for changing the pressure in said fuel, a heater for said fuel, and means for controlling said retardation means in response to a change in the temperature of said fuel. 30
